UNITED STATES PATENT OFFICE.

ARTHUR C. PRINCE, OF CHICAGO, ILLINOIS.

REGISTERING BANK.

Application filed March 21, 1923. Serial No. 626,554.

This invention relates to a coin bank, and particularly to a registering coin bank, wherein a recording mechanism is mounted which indicates the number of coins inserted.

- 5 The bank is intended primarily for use with only one kind of coin, but it is not limited to this use. The bank here illustrated is intended particularly for use with ten cent pieces. It is arranged to indicate the number of such pieces inserted. The objects of 10 the invention will appear from time to time throughout the specification and claims.

My invention is illustrated more or less diagrammatically in the accompanying drawings, wherein:

Figure 1 is an elevation of the rear of the bank;

Figure 2 is an elevation of the front of the bank with parts broken away;

20 Figure 3 is a vertical cross section through the bank shown on an enlarged scale;

Figure 4 is a horizontal cross section of the bank taken on line 4—4 of Figure 3;

25 Figure 5 is a vertical cross section on a further enlarged scale showing the slot and in greater detail the registering plate. It is taken on line 5—5 of Figure 4.

Like parts are indicated by like characters throughout.

30 The bank is formed of two main shells A, A¹. The shell A is provided with a downwardly depending flange A² about which the bottom plate A¹ is crimped. The plate A is provided with the opening A³, 35 preferably circular, within which is removably mounted a cover B. This cover B is provided with an engaging hook B¹ and a lock B², which may be of any suitable form, and forms no part of the present invention.

40 Fastened to the plate B may be an advertising disc B³ upon which the name of the bank or other institution issuing the small bank may appear. A similar plate C may be mounted on the bottom of the bank, that 45 is on the plate A¹.

Mounted within the bank and adapted to rotate is a registering plate or disc D. This disc as shown in the drawings is pivotally held on the bottom plate A¹ as at D¹. It is 50 provided with an upwardly extending flange D² which has about its upper edge a plurality of notches D³.

Mounted within the bank and forming part of this structure is a liner E, which is 55 crimped into the structure so as to hold it fixedly. This liner is throughout a portion

of its circumference provided with the raised part E¹ and forms with the part A² a cavity within which a slider F is mounted. This slider is provided in its bottom and preferably at one end with a pawl F² adapted to engage the notches D³. The liner E is provided adjoining the portion E¹ with an enlarged outwardly bent portion F³. Within this portion lies a spring G. This spring 60 bears against the end of the slider F and normally holds it in the position shown in Figure 3 so that a part of it overhangs the slot H in the wall of the bank. F⁴ is a spring which yieldingly holds the slider F in the 65 position shown in Figure 3.

The plate A¹ of the bank is provided with a perforation I, and the moving plate D is marked with a plurality of numerals I¹, 70 one of which always shows through the perforation I.

Although I have shown an operative device, still it will be obvious that many changes in size, shape and arrangement of parts might be made without departing materially from the spirit of my invention, and I wish therefore that my showing be taken as in a sense diagrammatic.

The use and operation of my invention are as follows:

The parts are normally in the position shown in Figures 3, 4 and 5 with the slider masking a portion of the slot. When a coin is inserted it pushes the slider away, moving it laterally against the spring. When so moved, the pawl, which forms a part of the slider, engages one of the notches in the recording plate and moves it around. The parts are so proportioned that it is moved a distance sufficient only to move the plate 90 so as to change by one the number showing through the slot. After the coin has entered the bank, the spring moves the slider back and the pawl rides over the next slot and the parts are in the position for further operation.

Thus with each insertion of a coin the slider is moved and by its movement moves the registering plate and so changes the number visible through the casing of the 105 bank, indicating the insertion of another coin. By this progressive movement of the registering plate the number of coins in the bank is always indicated and is always visible from outside.

I claim:

1. In combination in a pocket coin bank

having a coin slot and a curved double wall, such slot formed in such curved wall, a registering mechanism adapted to register the number of coins inserted into the bank, such mechanism including a numbered member, and means for moving such numbered member including a curved shutter located within such double wall mounted for movement and normally extending partly across such slot adapted to be moved by the insertion of a coin and provided with a projection which when the shutter is moved by the coin contacts one of the projections of the numbered member to move it, such shutter being guided and limited in its movement wholly by such double wall.

2. In combination in a pocket coin bank having a coin slot and a curved double wall, such slot formed in such curved wall, a registering mechanism adapted to register the number of coins inserted into the bank, such mechanism including a numbered member lying within such bank, open to the interior thereof, and means for moving such numbered member including a curved shutter located within such double wall mounted for movement and normally extending partly across such slot adapted to be moved by the insertion of a coin and provided with a projection which when the shutter is moved by the coin contacts one of the projections of the numbered member to move it, such shutter being guided and limited in its movement wholly by such double wall.

3. A registering bank having a casing with ends and intermediate side walls through which latter is a coin slot, in combination with a registering mechanism supported close to one of the ends, a shutter within the bank casing located close to the side wall, movable to partially cross the coin slot so as to be operated by the insertion of a coin, the shutter carrying a part to engage with and operate the registering mechanism and means carried by the side

wall of the casing of the bank for holding the shutter close to the inner face of said wall and for directing its movement.

4. In a pocket bank having a curved side wall in which is a coin slot, a registering mechanism adapted to register the coins inserted, including a circular dial pivoted for rotation within the said bank, provided about its edge with an upturned flange in which a plurality of teeth are formed, in combination with a movable shutter located within the bank and supported close against the inner side wall and adapted to normally shut off a portion of the said coin slot, and provided with a projecting member adapted to engage with the teeth of the said dial the shutter being adapted to be moved laterally by the insertion of a coin and in such movement through its said projecting member adapted to engage one of the teeth of the dial and rotate the same to record the insertion of a coin, and means carried by the said wall of the bank for holding the shutter close to the face of the wall and for directing its movements.

5. In a pocket bank a cylindrical side wall having a coin slot through it, a coin registering dial provided with numbers, a curved shutter formed concentrically with and located close against the inner face of the cylindrical side wall, said shutter normally closing part of the said coin slot, and adapted to be moved concentrically with the curved wall by the insertion of a coin, said shutter being provided with an extension adapted to directly engage said dial to move the same in direct response to the movement of said shutter as the coin is inserted, and means for guiding the shutter and limiting its movement carried by the curved side wall.

Signed at Chicago, county of Cook and State of Illinois, this 17th day of March, 1923.

ARTHUR C. PRINCE.
